UNITED STATES PATENT OFFICE

2,040,077

TABLE AND BOOK LEDGE

Robert C. Burnley, Louisville, Ky.

Application June 25, 1934, Serial No. 732,343

8 Claims. (Cl. 45—82)

This invention relates to a table and book ledge and constitutes a reading desk.

One of the important features of the present invention is the production of a simple and efficient stand or table which is so constructed as to efficiently support a book or other reading matter in a manner whereby the book-engaging member may be adjusted at a desired angle to facilitate the reading of the book or other matter which is supported upon the book-engaging member.

A further object of this invention is the production of a simple and efficient supporting standard for a book-engaging member or desk whereby the desk may be adjusted vertically and also the angle of the book-supporting member or desk may be similarly adjusted.

A further object of this invention is the production of a simple and efficient book-supporting desk which is so constructed as to permit various sizes of book-supporting panels or plates to be secured to the desk.

Other objects and advantages of the present invention will appear throughout the following specification and claims.

In the drawings:

Figure 1 is a front elevation of the improved table and book ledge, certain parts being broken away and shown in section;

Figure 2 is a side elevation of the standard which supports the book ledge or desk illustrating the reading desk supported upon the standard and also showing a portion of the standard supporting frame;

Figure 3 is an enlarged vertical section through a portion of the lower section of the book ledge-supporting standard illustrating the manner in which the adjustable section is mounted within the stationary section of the standard;

Figure 4 is a top plan view of the book ledge or desk, the lamp-supporting tray, as well as the supporting standard and a portion of the standard supporting frame or table;

Figure 5 is a section taken on line 5—5 of Figure 4;

Figure 6 is an enlarged bottom plan view of the book ledge or desk and illustrating the lamp supporting tray and means for holding the desk and tray in adjusted angular relation;

Figure 7 is a section taken on line 7—7 of Figure 5;

Figure 8 is a section taken on line 8—8 of Figure 5;

Figure 9 is an enlarged top plan view illustrating the book-clamping means carried along the lower edge of the book ledge or desk;

Figure 10 is an edge elevation of the bottom portion of the book ledge or desk illustrating the manner of gripping the lower edge of a book for holding the book in position;

Figure 11 is a section taken on line 11—11 of Figure 9;

Figure 12 is an edge elevation of the lower edge of the book ledge or reading desk showing the manner of mounting the lower section upon the upper section of the desk to accommodate different sized books, a portion of the lower section being broken away;

Figure 13 is a section taken on line 13—13 of Figure 12;

Figure 14 is an inverted perspective view of the upper section of the reading desk or book ledge, a certain portion of the book-clamping means being shown in section.

By referring to the drawings, it will be seen that 10 designates a table which comprises a base 11 which is supported upon suitable legs 12. The base 11 supports a plurality of corner standards 13 which standards in turn support a top 14 and an intermediate shelf 15. An adjustable standard 16 is carried by the table 10 and comprises a hollow internally threaded tubular base section 17 which is anchored upon the base 11 through the medium of a socket member 18. The base section 17 comprises an elongated tubular structure which extends vertically through the center of the shelf 15 and also through the top 14, as shown in Figure 1. The base section 17 is externally threaded at its upper end and supports a cap 19 which cap 19 carries a thumb screw 20 for the purpose of engaging the adjustable shank 21 of the standard 16. The adjustable shank 21 is provided with an enlarged lower end 22 which carries an enlarged externally threaded head 23 engaging the internal threads 24 of the base section 17, as shown in Figure 1. The adjustable shank 21 by rotation may be adjusted longitudinally of the base section 17 to raise and lower the shank 21 to the position shown in dotted lines in Figures 1 and 2 when desired. When the adjustment desired is obtained, the shank 21 may be locked in position against rotation as well as longitudinal adjustment through the medium of the locking screw 20.

It is preferable that the table 10 may be of sufficient weight to properly support the standard 16 and prevent the device from toppling over. One of the supporting legs extends laterally of the table, as indicated by the numeral 12a for the purpose of bracing the table and

preventing the table from tipping over under the weight of the reading desk.

The adjustable shank 21 may be provided with spaced aperture 21a arranged within the length 5 of the shank 21 and a pin 11a may extend through the base section 17 and through the aperture 21a for locking and rigidly holding the shank 21 in an adjusted or set position at a suitable height.

10 If so desired, the enlarged end 22 may constitute a portion of the shank 21 or may be formed integrally therewith and the threaded part 23 may also be formed as an integral portion without departing from the spirit of the 15 invention.

The shank 21 of the standard 16 is provided with a laterally extending arm 25 at its upper end which arm 25 supports a lamp carrying tray 26. This lamp carrying tray 26, as is illustrated 20 in detail in Figures 5 and 6 is provided upon the bottom thereof with a tubular supporting casing 27 through which the arm 25 extends. Fixed upon the arm 25 is a collar 28 which is engaged by an expansion coil spring 29 the opposite end of the coil spring 29 contacting with the end wall 30 of the tubular supporting casing 27. The collar 28 carries a projecting pin 31 which works in a longitudinally extending slot 32 formed at the bottom of the tubular casing 30 25 31, as shown in Figures 5 and 6. In view of this structure, it will be seen that the lamp carrying tray 26 may be shifted from right to left for the purpose of compressing the coil spring 29 and drawing the locking arm 33 which 35 is carried by the tubular supporting casing 27 out of adjustable engagement with the apertures 34 formed in the adjusting rack 35 of the book supporting desk 36 hereinafter described. The coil spring 29 is adapted to normally urge the 40 tray 26 toward the right for the purpose of holding the locking arm 33 in an adjusted position with the rack 35. As shown in Figure 8, the adjusting apertures 34 in the rack 35 are preferably arranged on the arc of a circle with the 45 arm 25 acting as a pivot or bearing. In this way, the angle adjustment of the book supporting desk 36 may be obtained by causing the arm 33 to selectively engage one of the apertures 34 of the rack 35.

50 The reading desk or book ledge 36 preferably comprises an anchored section 37 which is secured to the arm 25 by means of a supporting journal 38 and slidably mounted upon the anchored section 37 is a laterally adjustable or 55 sliding section 39 whereby the sections may be spread laterally to accommodate different width books or other matter to be supported upon the book ledge 36. The stationary section 37 is preferably provided with overturned flanges 40 under which fit the edges of the adjustable section 39, as shown in Figure 4. The adjustable section 39 carries an adjusting sleeve 41 upon the bottom thereof which is slidably mounted upon the arm 25 and a suitable locking screw 42 60 is carried by the sleeve 41 for engaging the notches 43 in the arm 25 whereby the sections may be locked in a selected adjusted position. The adjusting sleeve 41 is provided with an elongated slot 44 in which the locking screw 42 65 is mounted to hold the sleeve against longitudinal movement upon the arm 25 but at the same time permit a limited rotation of the reading desk or book ledge relative to the supporting arm 25 to permit of a proper angular adjustment to 70 suit the convenience of the user. This angular 75

adjustment, as previously described, may be obtained by shifting the lamp supporting tray 26 to the left and permitting a proper adjustment of the arm 33 in one of the selected apertures 34 of the rack 35. The sections 37 and 39 of the desk or book ledge are preferably formed of sheet metal and longitudinally of the sections are formed the interfitting web portions 45 to reinforce and also to facilitate the convenient sliding of a section with respect to the other. 10 Each of the sections 37 and 39 is provided along its side edge with an upstanding flange 46 carrying a longitudinally grooved track member 47, as shown in Figure 5. Should it be necessary to use a larger book supporting plate upon the 15 desk or book ledge, an enlarged plate 48 may be employed, such as shown in Figure 12 and Figure 14, the enlarged plate having a depending casing 49 upon the bottom thereof with beaded rails 50 formed upon the side edges which are 20 adapted to fit in the longitudinally grooved track members 47 and permit the attachment of the enlarged plate 48 into position. This plate 48 may have its edges 50a overturned for supporting 25 a glass or other panel 51.

The reading desk or book ledge 36, as well as the enlarged plate 48, may be each provided along its bottom edge with book engaging clamps 52 and 53 respectively, each being similarly constructed. The various parts of each clamp will be 30 referred to by the same reference character in view of the duplicate mechanical structure used in each instance. Each of these clamps is anchored in position by means of supporting members 54 of any suitable or desired structure, and 35 each clamping member comprises an elongated base 55 carrying a hinging rod 56 which is journaled thereon, the hinging rod 56 having angularly bent fingers 57. Slidably mounted upon these angularly bent fingers 57 is an upper clamping bar 58 which clamping bar carries an operating handle 59. A retaining plate 60 is carried by the front edge of the base 55 in each instance to constitute an abutment against which the 40 clamping bar 58 may rest, and also to limit the 45 swinging movement of the fingers 57. Coil springs 61 are connected to the ends of the base 55 and the adjustable clamping bar 58, as shown in Figures 9 and 10, and normally draws the 50 clamping section 58 tightly upon the base section 55 so as to cause the lower edge of the book engaging section 58 to engage the upper face of the lower edge of the book cover 62, as shown in 55 Figure 11 in dotted lines and in full lines in Figure 13. In this way, the book will be firmly held in position against accidental displacement and the clamping section 58 may be readily disengaged from the book merely by a pull upon the handle 59, and as soon as the handle is released the 60 springs 61 will draw the clamping section 58 to a clamping position.

From the foregoing description, it will be seen that the reading desk or book ledge may be conveniently adjusted with respect to the lamp supporting tray 26 and a lamp of any suitable or desired type indicated by the dotted lines and also by the numeral 63 may be supported upon the tray 26. The standard 21 may also be adjusted to suit the desired height, and by mounting the lamp supporting tray 26 for lateral shifting movement, the lamp supporting tray being held against rotating movement upon the arm 25 and the desk or book ledge 36 being mounted for swinging movement upon the arm, a proper 70 75 77 78 79 80 81 82 83 84 85 86 87 88 89 90 91 92 93 94 95 96 97 98 99 100 101 102 angular adjustment of the desk or book ledge may be obtained.

It should be understood that certain detail changes in the mechanical construction, combination or arrangement of parts may be employed without departing from the spirit of the invention, so long as such changes fall within the scope of the appended claims.

Having described the invention, what is claimed 10 as new is:—

1. A device of the class described comprising a supporting member, an anchoring member reciprocably mounted upon said supporting member, spring means carried by said supporting member 15 and engaging said anchoring member for normally holding the anchoring member in one position and permitting the shifting of the anchoring member to another position, the spring means holding the anchoring member against rotation 20 upon said supporting member, said anchoring member having a projecting locking arm, a reading desk journaled for rotating movement upon said supporting member, said reading desk having a rack for engagement with said locking arm, 25 said rack having a plurality of apertures arranged on the arc of a circle for receiving said locking arm whereby said reading desk may be held in an adjusted angular position upon said supporting member, said anchoring member constituting 30 a lamp supporting tray and a tubular portion fitting around said supporting member and housing said spring means, said spring means embodying a collar fixed on said supporting member and a compression spring, the tubular portion 35 being longitudinally slotted and said collar having a pin working in said slot for permitting the longitudinal shifting of the tubular portion with respect to the supporting member and at the same time holding the tubular portion against rotation 40 upon said supporting member.

2. A device of the class described comprising a support, a reading desk carried thereby, said reading desk comprising a plurality of laterally adjustable sections, track rails carried by the sides 45 of the reading desk, and a removable plate removably engaging said track rails.

3. A device of the class described comprising a support, a reading desk carried thereby, said reading desk comprising a plurality of laterally adjustable sections, track rails carried by the sides 50 of the reading desk, a book supporting plate adapted to be detachably secured upon said reading desk, and said book supporting plate having a depending frame carrying longitudinally extending track members for fitting in said track rails of said reading desk whereby said book supporting plate may be detachably supported upon said reading desk.

4. A device of the class described comprising a 60 supporting member, a reading desk carried thereby, a book edge engaging clamp carried by said

reading desk comprising a base member and a clamping section, means carried by the base member and engaging the clamping section for hingedly securing the clamping section upon said base member, and means for bodily moving said clamping member away from said base member. 5

5. A device of the class described comprising a reading desk, a book edge engaging clamp carried by said reading desk, said book engaging clamp comprising a base, a clamping section, a hinging 10 rod secured to the base, said hinging rod having angularly bent end portions, said clamping member being slidably mounted upon said angularly bent end portions whereby the clamping member may be hinged upon the base member and also 15 bodily moved away from said base member, an operating handle carried by the clamping member, and spring means for normally drawing the clamping member to a clamping position with 20 respect to the base.

6. A device of the class described comprising a supporting rod normally extending in a substantially horizontal position, journals carried by said rod, a reading desk carried by the journals, said reading desk comprising a plate having a longitudinally extending beaded portion, said journals having sockets for receiving said beaded portion for facilitating the anchoring of the desk upon the journals, and book supporting means carried 25 by the desk.

7. A device of the class described comprising a supporting member, an anchoring member reciprocably mounted upon said supporting member, a spring carried by the supporting member, means anchored upon said supporting member and engaging said anchoring member whereby said anchoring member will be held against rotation upon said supporting member and at the same time may have reciprocating movement upon the supporting member, a projecting locking arm carried by said anchoring member, a desk rotatably mounted upon said supporting member, means for limiting the rotating movement of the desk upon said supporting member, said desk having a rack provided with a plurality of sockets arranged 40 in alignment to receive said projecting locking arm whereby said desk may be held in an adjusted angular position with respect to said anchoring member. 35

8. A device of the class described comprising a support, a reading desk mounted for rotary movement and longitudinal adjustment upon said support wherein the angular position of said desk may be adjusted, means for holding said reading desk in an adjusted angular position upon said support, and means for locking said desk in an adjusted position with respect to the length of said support and also limiting the rotary movement of said desk upon said support. 50
